[57] CLAIM

The ornamental design for an ultrasonic transducer
with holding assembly for use in reducing ocular pres-
sure of the eye, substantially as shown.

DESCRIPTION

FIG. 1 is a perspective view of an ultrasonic transducer
with holding assembly for use in reducing ocular pres-
sure of the eye showing my new design;

FIG. 2 is a front elevational view thereof;

FIG. 3 is a back view thereof;

FIG. 4 is a top plan view thereof;

FIG. 5 is a left side elevational view thereof; and

FIG. 6 is a right side elevational view thereof.

FIG. 1

FIG. 2

FIG. 3

FIG. 4

FIG. 5

FIG. 6
